POOL TABLE

Erwin Benkoe, New Hyde Park, N.Y., assignor to Ideal
Toy Corporation, Hollis, N.Y.

Filed May 10, 1966, Ser. No. 2,241

Term of patent 7 years

(Cl. D34—3)

FIG. 1

FIG. 2

FIG. 3

FIG. 4

FIG. 5

FIG. 1 is a top plan view of a pool table embodying my new design;

FIG. 2 is a side elevational view;

FIG. 3 is a bottom plan view;

FIG. 4 is a left end elevational view; and

FIG. 5 is a right end elevational view.

I claim:

The ornamental design for a pool table, as shown.
